ROBERT WARRINER, OF BRAINTREE, MASSACHUSETTS, ASSIGNOR TO BETHLEHEM
SHIPBUILDING CORPORATION.

FEED TANK.

Application filed June 1, 1925. Serial No. 33,979.

It is the practice in many steam power plants to withdraw the water of condensation and the non-condensable gases from the condenser separately, using pumps for the condensate and steam jet ejectors for the non-condensable gases. The ejectors sometimes discharge the mixture of steam and gas, the gases consisting principally of air, into a compartment of a feed tank where it is mixed with the water of condensation discharged by the pumps. The water of condensation condenses the condensable portion of the media discharged from the ejector and also absorbs a part of the air, the remainder of the air being discharged from the compartment through a vent. The water, with the dissolved air, ultimately flows to the feed pumps from which it is discharged through the feed system to the boilers.

The presence of dissolved air in the feed water is responsible for corrosion of boilers, piping, and other apparatus, for example, turbine blading. Accordingly, therefore, the object of my invention is to provide, in connection with a main power plant condenser and its steam actuated air ejector, feed tank apparatus which serves to recover water and heat from media discharged from the air ejector by means of condensate coming from the condenser without the latter absorbing any air contained in the discharged media, which serves to filter the condensate, and which provides for a main feed supply constituted by the condensate used in a cooling relation with respect to the media discharged from the air ejector and by the water of condensation recovered from such discharged media.

Apparatus made in accordance with my invention is illustrated in the accompanying drawings, forming a part of this application, in which:

Fig. 1 is a diagrammatic view showing my improvement applied to a power plant installation;

Fig. 2 is a horizontal sectional view of the feed tank, taken along the lines II—II of Fig. 7;

Fig. 3 is a longitudinal sectional view of the feed tank shown in Figs. 1 and 2 and taken along the line III—III of Fig. 2; and,

Figs. 4, 5, 6 and 7 are sectional views taken

along the lines IV—IV, V—V, VI—VI and VII—VII of Fig. 3.

Referring now to the drawings for a better understanding of my invention, I show a main power plant condenser 10 having a condensate discharge passageway 11 communicating with a hot well 12. The passageway 11 is provided with the usual condensate pump 13 of any suitable type. The condenser 10 is provided with any suitable form of steam-actuated ejector 14 for the removal of air from the air space 15 of the condenser. The passageways 16 and 17 conduct water of condensation discharged from the pump 13 and discharged media from the air ejector 14, respectively, to compartments of the feed tank 18, where the water of condensation serves to absorb heat from the discharged media of the air ejector to condense the condensable portion thereof without any opportunity being afforded for air from the discharged media being absorbed by the water of condensation.

Referring now to the apparatus for absorbing heat from the ejector discharge media by condensate from the main condenser without absorption of air while permitting of the recovery of the condensable portion of the discharged media, I show feed tank apparatus, at 18, including a main tank 19 having a horizontal partition or wall 20 in its upper portion. The partition 20 cooperates with vertical partitions 21, 22, 23, 24 and 25 and with side and top tank walls to define a series of chambers 26, 27, 28, 29 and 30.

Condensate from the main condenser 10 is admitted to the first chamber 26 and then flows through condenser tubes 31 disposed in the chamber 27 and carried by the tube plates 32 and 33 fitting over the openings 34 and 35 in the partitions 21 and 22, respectively. The partition 23 between the chambers 28 and 29 has its upper portion cut away, as indicated at 36, to permit of the passage of water from the chamber 28 to the chamber 29. Water then passes through the filtering devices arranged in the chambers 29 and 30 and then over the overflow wall 37.

The filters disposed in the chambers 29 and 30 preferably comprise filtering material 38 arranged between upper and lower

pairs of foraminous plates 39 and 40, the pairs of plates 39 and 40 carried by the partitions 23 and 24 and 23^a and 25, respectively.

5 The lower plate 40 of the chamber 29 and the partition 24 are arranged a sufficient distance above the horizontal partition 20 and the partitions 24 and 23^a are spaced a sufficient distance apart to provide a passageway 41 for conducting condensate passing from the bottom of the filter chamber 29 to the top portion of the filter chamber 30. In like manner, the bottom plate 40 of the second filter chamber and the partition 25 are 10 spaced sufficiently above the partition 20 and the partition 25 is spaced a sufficient distance from the overflow wall 37 to provide for a passageway 41' leading from the bottom of the second filter chamber to the top 15 of the wall 37.

While I have shown and described two filter chambers 29 and 30, it will be apparent to those skilled in the art that the number of chambers may be varied without departing from the spirit of my invention. After 20 passage from the last filter chamber, condensate enters the main feed tank chamber 42.

Media discharged from the air ejector 14 25 passes through the conduit 17 and enters laterally of the chamber 27 and enters the inlet 44 in a side wall of the chamber. The bank of tubes 31 is so disposed as to provide a lane 45 having its inlet positioned adjacent to the inlet 44 and it serves to secure distribution of media about the tubes. Reflectors 46 and 47 are arranged, respectively, above and below the inlet 44 and they serve to direct the media coming from the ejector 30 through the lane 45 and between the tubes. A vent 48 communicates with the upper portion of the chamber 27 and permits of the escape of non-condensable vapors and gases to the atmosphere. The bottom wall of the 35 chamber 27 has an opening 49 therein which permits of the passage of the condensable portion of the media into the tank chamber proper.

From the apparatus so far described, it 40 will be apparent that condensate from the main power plant condenser 10 passes through the tubes 31 and that it is warmed by heat absorbed from the media discharged from the air ejector 14 and entering the chamber 27 and passing about the tubes 31. The non-condensable gases or vapors escape to the atmosphere through the vent 48 while the condensed portion of such media enters the main tank chamber through the outlet 49. In this way, heat and water are recovered from the ejector discharge without involving any admixture of the condensate with the ejector discharge and the incidental absorption of a portion of air by the condensate. 45

Should the rate of supply of condensate to the chamber 26 exceed the passage capacity of the tubes 31, then a by-pass including conduit sections 50 and 51 permit of condensate passing around the chamber 27 from the chamber 26 to the chamber 28. 70

In view of the fact that the steam consumption from an air ejector is fairly constant while the amount of water or condensation varies with the load, it is possible, at 75 low loads, that insufficient water may pass through the tubes 31 to condense all of the steam from the media discharged from the ejector. I, therefore, provide means for bypassing a portion of the condensate after it has passed through the tubes 31 back into the main condenser 10 where it is cooled; and such by-passed portion of condensate then augments the condensate corresponding to the load and assures that the rate of flow 80 through the tubes 31 shall be sufficient to condense the condensable portion of the media discharged from the ejector. 85

To this end, I show a conduit 52 communicating with the condenser 10 and with the feed tank apparatus, the conduit containing a valve 53, which is under the control of a thermostat 54. The thermostat 54 is responsive to the temperature of water at the down-stream side of the tube bank and it is preferably arranged in the chamber 28. 90

If the temperature of water in the chamber 28, or at the downstream side of the bank of tubes 31, should exceed a predetermined amount, for example, 150° F., the thermostat 54 operates to open the valve 53, whereupon water flows from the feed tank apparatus through the conduit 52 into the condenser 10. While I show the conduit 52 communicating with the chamber 28, it will be apparent to those skilled in the art that this conduit may communicate with any part of the feed tank apparatus following the bank of tubes, the only requirement being that condensate shall have passed through the tubes 31 before being returned to the main condenser 10 for re-passage through the tubes. 95

The operation of apparatus made in accordance with my invention will be apparent 100 from the foregoing description. Condensate enters the chamber 26 from the main condenser 10 and passes through the tubes 31. At the same time, media discharged from the ejector 14 enters the chamber 27 and passes about the tubes 31. Heat is transferred by the heat conductive walls of the tubes from the media discharged from the ejector to the condensate passing through the tubes, with the result that the condensate 105 has its temperature increased and the condensable portion of the discharged media is recovered, such condensable portion passing through the outlet 49 from the chamber 27 to the main tank chamber where it joins 110

the main condensate feed supply. Air and non-condensable vapors pass from the upper portion of the chambers 27 to the atmosphere through the vent 48. In case the rate 5 of supply of condensate to the chamber 26 should exceed the capacity of the tubes 31, the excess of condensate is by-passed by the conduits 50 and 51 to the chamber 28. If the power plant load should be so low that 10 the rate of flow of condensate through the tubes 31 becomes insufficient to condense the condensable portion of the media entering the chamber 27 from the air ejector 14 and to absorb heat to the best advantage, then 15 it will be apparent that the condensate leaving the tubes 31 will have its temperature increased; and when the temperature of water in the chamber 28 reaches a predetermined amount, for example, 150° F., the thermostat 20 54 comes into play to open the valve 53, whereupon water passes from the feed tank apparatus back to the main condenser 10 in order to augment the supply of condensate, such water being cooled by the tubes of the 25 main condenser, so that an adequate supply of condensate at a suitable temperature is available to assure complete condensation of the condensable portion of the media discharged from the air ejector and the absorption 30 of heat from such media to the best advantage. After the condensate passes through the tubes 31 and the chamber 28, it enters the chambers 29 and 30, where it passes through the filtering material, for 35 example, loofa, in order to have undesirable materials filtered out.

While I show feed tank apparatus employing filtering devices, it will be apparent that, in so far as recovery of heat and water from the discharged media from the ejector without admixture of air of such media with the cooling condensate is concerned, the filtering devices might be omitted. Furthermore, while I show a single ejector discharging to the feed tank apparatus, it will be obvious that any suitable number may be employed.

While I have shown my invention in but one form, it will be obvious to those skilled in the art that it is not so limited, but is susceptible of various other changes and modifications without departing from the spirit thereof, and I desire, therefore, that only such limitations shall be placed thereupon as are imposed by the prior art or as are specifically set forth in the appended claims.

Having thus described the invention what I claim as new and desire to secure by Letters Patent is:

1. In a feed tank for a steam power plant, in combination, an inlet chamber for condensing water, a condensing chamber adjacent thereto, an additional chamber adjacent to the condensing chamber, tubes passing

through the condensing chamber and connecting the inlet chamber with said additional chamber, means for admitting a heating medium to the condensing chamber and for securing the distribution thereof about 70 the tubes, and a feed reservoir for receiving condensing water from the additional chamber.

2. In a feed tank for a steam power plant, in combination, an inlet chamber for condensing water, a condensing chamber adjacent thereto, an additional chamber adjacent to the condensing chamber, tubes passing through the condensing chamber and connecting the inlet chamber with said additional chamber, means for admitting steam 75 to the condensing chamber and for securing the distribution thereof about the tubes, a feed reservoir for receiving condensing water from the additional chamber, and means for conducting condensate from the condensing chamber to the feed reservoir.

3. In a feed tank for a steam power plant, in combination, an inlet chamber for condensing water, a condensing chamber adjacent thereto, an additional chamber adjacent to the condensing chamber, tubes passing through the condensing chamber and connecting the inlet chamber with said additional chamber, means for admitting steam 80 to the condensing chamber and securing the distribution thereof about the tubes, one or more filter compartments for receiving condensing water from the additional chamber, and a feed reservoir for receiving condensing water from the filter compartment or compartments.

4. In a feed tank for a steam power plant, in combination, an inlet chamber for condensing water, a condensing chamber adjacent thereto, an additional chamber adjacent to the condensing chamber, tubes passing through the condensing chamber and connecting the inlet chamber with said additional chamber, means for admitting steam 105 to the condensing chamber and for securing suitable distribution thereof about the tubes, means for conducting an excess of water from the inlet chamber to said additional chamber, and a feed reservoir for receiving condensing water passing from the additional chamber.

5. In a feed tank for a steam power plant, in combination, an inlet chamber for condensing water, a condensing chamber adjacent thereto, an additional chamber adjacent to the condensing chamber, tubes passing through the condensing chamber and connecting the inlet chamber with said additional chamber, means for admitting steam 110 to the condensing chamber and for securing suitable distribution thereof about the tubes, means responsive to the temperature of water discharged from said tubes for maintaining a sufficient supply of condensing 115

water to the inlet chamber, and a feed reservoir for receiving condensing water passing from said additional chamber.

6. In a feed tank for a steam power plant, in combination, an inlet chamber for condensing water, a condensing chamber adjacent thereto, an additional chamber adjacent to the condensing chamber, tubes passing through the condensing chamber and connecting the inlet chamber with said additional chamber, means for admitting steam to the condensing chamber and for securing suitable distribution thereof about the tubes, means responsive to the temperature of water discharged from said tubes for maintaining a sufficient supply of condensing water to the inlet chamber, one or more filter compartments for receiving water passing from said additional chamber, and a feed reservoir for receiving water discharged from the filter compartment or compartments.

7. In a feed tank for a steam power plant, in combination, an inlet chamber for condensing water, a condensing chamber adjacent thereto, an additional chamber adjacent to the condensing chamber, tubes passing through the condensing chamber and connecting the inlet chamber with said additional chamber, means for admitting steam to the condensing chamber and for securing its distribution about the tubes, means for conducting excess of water from the inlet chamber to said additional chamber, one or more filter compartments for water passing from the additional chamber, and a feed reservoir for receiving water discharged from the filter compartment or compartments.

8. In a feed tank for a steam power plant, in combination, an inlet chamber for condensing water, a condensing chamber adjacent thereto, an additional chamber adjacent to the condensing chamber, tubes passing through the condensing chamber and connecting the inlet chamber with said additional chamber, means for admitting steam to the condensing chamber and for securing its distribution about the tubes, means for conducting excess of water from the inlet chamber to said additional chamber, means responsive to the temperature of water discharged from said tubes for maintaining a sufficient supply of relatively cold water to the inlet chamber, and a feed reservoir for receiving water passing from said additional chamber.

9. In a feed tank for a steam power plant, in combination, an inlet chamber for condensing water, a condensing chamber adjacent thereto, an additional chamber adjacent to the condensing chamber, tubes passing through the condensing chamber and connecting the inlet chamber with said additional chamber, means for admitting steam to the condensing chamber and for distrib-

uting it about the tubes, means for conducting excess of water from the inlet chamber to said additional chamber, means responsive to the temperature of water discharged from said tubes for maintaining a sufficient supply of relatively cold water to the tubes, one or more filter compartments for receiving water passing from the additional chamber, and a feed reservoir for receiving water passing from the filter compartment or compartments.

10. The combination, with a steam-actuated air ejector, of a feed reservoir having a main feed chamber, a series of chambers disposed in the upper part of the reservoir, condenser tubes for affording communication between the first and third chambers of said series, means for admitting water to the first chamber, overflow means for discharging water from the last chamber of the series into the main chamber of the reservoir, means for admitting media discharged from the ejector to the second chamber and for securing its distribution about the tubes passing through the latter chamber, and outlet means from the second chamber to the atmosphere and to the main chamber of said reservoir.

11. The combination, with a steam-actuated air ejector, of apparatus having a series of chambers, condenser tubes for affording communication between the first and third chambers, means for admitting water to the first chamber, filtering material in the last chamber, overflow outlet means for the last chamber, means for admitting media discharged from the ejector to the second chamber, and outlet means from the second chamber for the condensable and non-condensable portions of said media.

12. The combination, with a steam-actuated air ejector, of apparatus having a series of chambers, condenser tubes for affording communication between the first and third chambers of said series, means for admitting water to the first chamber, overflow outlet means for the third chamber, overflow bypass means between the first and third chambers, means for admitting media discharged from the ejector into the second chamber, and separate means for securing the discharge of the non-condensable and condensed portions of said discharged media from the second chamber.

13. In a power plant, the combination with a condenser and its air ejector, of apparatus including a series of chambers, a tube bank for affording communication between the first and third chambers, means for conducting condensate from the condenser to the first chamber, outlet means for the last chamber of the series, means for admitting media discharged from the ejector to the second chamber, vent means for the non-condensable portion of said media commun-

cating with the second chamber, outlet means for the condensable portion of said media communicating with the second chamber, a conduit connecting the main condenser with 5 said apparatus at the downstream side of the tube bank, a valve in said conduit, and a thermostat in a chamber following the tube bank and connected to said valve.

14. In a power plant, the combination 10 with a main condenser and its air ejector, of apparatus including a series of chambers, a tube bank for affording communication between the first and third chambers, means for conducting condensate from the condenser to the first chamber; outlet means for the last chamber of the series, means for by-passing excess of condensate around the tube bank, means for admitting the media discharged from the ejector to the second 20 chamber, vent means for the non-condensable portion of said media communicating with the second chamber, and outlet means for the condensable portion of said media communicating with the second chamber.

25 15. In a power plant, the combination, with a main condenser and its air ejector, of apparatus including a series of chambers, a tube bank arranged in the second chamber and affording communication between the 30 first and third chambers, means for admitting condensate from the condenser for the first chamber, outlet means for the last chamber, means for admitting media discharged from the ejector to the second chamber, separate outlet means for condensable and non-condensable portions of said media communicating with the second chamber, an overflow passage between the first and third chambers, a passage between the apparatus 35 at the downstream side of the tube bank and the main condenser, a valve in the passage-way, and means responsive to the temperature of water in the third chamber for controlling the operation of said valve, whereby, when the water temperature in the third chamber exceeds a predetermined amount, the valve is opened and water is allowed to 40 pass from the apparatus to the main condenser.

50 16. In a power plant, the combination, with a condenser and its steam-actuated air ejector, of feed tank apparatus for receiving condensate from the condenser and for condensing the condensable portion of media 55 discharged from the ejector including a chamber containing condenser tubes followed by a chamber containing filtering material, means for passing condensate from the condenser through the tubes and then into the filter chamber, overflow means at the discharge side of the filter chamber for discharging condensate into the main tank chamber, means for admitting discharged media from the air ejector to the chamber 60 containing the condenser tubes, vent means

communicating with the upper portion of the last-named chamber to the atmosphere, and outlet means communicating with the lower portion of the last-named chamber and opening into the main tank chamber. 70

17. In a power plant, the combination, with a condenser and its steam-actuated air ejector, of feed tank apparatus for receiving condensate from the condenser and for condensing the condensable portion of media 75 discharged from the ejector including a chamber containing condenser tubes followed by a chamber containing filtering material, means for passing condensate from the condenser through the tubes and then 80 through the filter chamber, overflow means at the discharge side of the filter chamber for discharging into the main tank chamber, means for admitting media discharged from the ejector laterally of the 85 chamber containing condenser tubes, vent means communicating with the upper portion of the last-named chamber for permitting of the escape of noncondensable vapors and gases therefrom, outlet means communicating with the lower portion of the last-named chamber to permit of the passage of the condenser portion of said media into the main tank chamber, by-pass means arranged 90 between the feed tank apparatus and the condenser, a valve in the by-pass means, and means responsive to the attainment of a predetermined temperature by the condensate at the downstream side of the said condenser tubes for opening said valve. 95

18. In a power plant, the combination, with a condenser and its steam-actuated air ejector, of feed tank apparatus for receiving condensate from the condenser and for condensing the condensable portion of media 105 discharged from the ejector including serially arranged chambers at the top portion of the tank, a tube bank for affording communication between the first and third chambers, means for admitting condensate 110 from the condenser to the first chamber, filtering material in the chamber following the third chamber, means affording communication between the third and fourth chambers, overflow means for permitting the discharge 115 of water from the filter chamber into the main tank chamber, means for admitting media discharged from the air ejector into the second chamber, a vent for air and non-condensable gases communicating with the top portion of the second chamber, an outlet at the bottom portion of the second chamber permitting of the condensed portion of 120 said media passing into the main tank chamber, and means for by-passing condensate from the first chamber around the second chamber when the supply exceeds a predetermined amount. 125

19. In a power plant, the combination, with a condenser and its steam-actuated air 130

15 ejector, of feed tank apparatus for receiving condensate from the condenser and for condensing the condensable portion of media discharged from the ejector including serially arranged chambers at the top portion of the tank, a tube bank in the second chamber and affording communication between the first and third chambers, means affording communication between the third chamber and its following chamber, means for admitting condensate to the first chamber, filtering material in the chamber following the third chamber, overflow means for determining the level of condensate leaving the last chamber, means for admitting media discharged from the air ejector to the second chamber, vent means communicating with the top portion of the second chamber for air and non-condensable gases, outlet means communicating with the bottom portion of the second chamber for discharging the condensed portion of said media into the tank chamber proper, a conduit communicating with the condenser and with the feed tank apparatus, a valve in the conduit, and means responsive to the temperature of water in the third chamber for opening the valve.

20 20. In a power plant, the combination, with a condenser and its steam-actuated air ejector, of feed tank apparatus for receiv-

ing condensate from the condenser and for condensing the condensable portion of media discharged from the ejector including serially arranged chambers at the top portion of the tank, a tube bank in the second chamber and affording communication between the first and third chambers, means for admitting condensate to the first chamber, filtering material in the chamber following the third chamber, overflow means for determining the level of condensate leaving the last chamber, by-pass means between the first chamber and a chamber following the tube bank, whereby excess of condensate entering the first chamber may be by-passed, means for admitting media discharged from the air ejector to the second chamber, vent means communicating with the top portion of the second chamber for air and non-condensable gases, outlet means communicating with the bottom portion of the second chamber for discharging the condensed portion of said media into the tank chamber proper, a conduit communicating with the condenser and with the feed tank apparatus, a valve in the conduit, and means responsive to the temperature of water in the third chamber for opening the valve.

25 In testimony whereof I hereunto affix my signature this 26th day of May, 1925.

ROBERT WARRINER.
